UNITED STATES PATENT OFFICE.

JAMES REGINALD KEMP, OF NEWBURY, ENGLAND.

TWO-STROKE-CYCLE INTERNAL-COMBUSTION ENGINE.

1,242,450.

Specification of Letters Patent.

Patented Oct. 9, 1917.

Application filed January 26, 1914. Serial No. 814,552.

To all whom it may concern:

Be it known that I, JAMES REGINALD KEMP, a subject of the King of Great Britain, and a resident of "Oakhurst," Woodhay, Newbury, Berkshire, England, have invented new and useful Improvements in Two-Stroke-Cycle Internal-Combustion Engines, of which the following is the specification.

10 This invention relates to improvements in two stroke cycle internal combustion engines.

The objects of this invention are (1) to provide a two stroke engine in which there shall be a practically perfect balance of the moving parts, (2) to provide a two stroke engine in which the combustion or working stroke takes place between two pistons connected to opposed cranks without any necessity for employing outside connecting rods, and (3) to provide a two stroke engine in which the pump faces of the two working pistons serve, the one as a mixture pump, and the other as a scavenging pump, thus obviating the necessity for the employment of an additional pump or valve.

My invention relates to that kind of engine in which in a single cylinder two annular pistons are fitted each formed with a tubular or trunk extension, the one adapted to slide within the other, and in which there are three crank pins on the crank shaft, one inner and two outer, the latter being placed at 180 degrees from the former. According to my invention, one end of each of the annular pistons serves as a pump to supply a central combustion chamber between the pistons, and a central channel open to the air at the upper end is formed through both piston trunks.

The inner sleeve trunk piston is connected by its connecting rod to the central crank pin. The flange forming the upper annular piston is preferably integrally formed at the extreme outer end of the sleeve or tube and may conveniently be formed hollow, or of double annular walls. The outer edge of the flange slides upon the cylinder wall and is of sufficient depth to carry suitable packing rings.

The second annular piston is at the extreme outer or upper end of its tube or trunk, and the outer surface is also provided with

suitable packing contacting with the cylinder wall. There is also preferably formed 55 integrally with the said head, a depending extension sleeve adapted to reciprocate in contact with the cylinder wall.

The cylinder cover is provided with an inner downwardly depending stationary tube 60 or sleeve fitting within the inner trunk piston. The interior of the stationary sleeve is open to the outer air.

The outer of the two sleeves, that carrying the lower annular piston is provided on its 65 exterior at its lower end with preferably, two pins or studs forming gudgeon pins, to which are connected two connecting rods fitting at their lower ends the two outer crank pins. The exterior surface of the outer tube 70 or piston trunk slides within a stationary sleeve or tube secured to the crank chamber, and closing the lower end of the cylinder. By this arrangement all connecting rods are within the crank chamber.

75 A ring of exhaust ports is formed in the outer cylinder wall adapted to be uncovered by the lower annular piston just prior to, and at the lower dead point of its stroke.

Shortly after the said exhaust ports are 80 uncovered, the upper annular piston uncovers passages formed longitudinally in the cylinder wall whereby the scavenging air is transferred from the pump side of the upper annular piston where it has been previously 85 compressed, to the working side thereof. As the scavenging air is thus delivered at the opposite end of the annular combustion chamber to that at which the exhaust gases leave the cylinder, the scavenging is more 90 efficient. Shortly after the delivery of scavenging air and preferably before the scavenging air ports are closed, the mixture is delivered by the pump at the other end of the cylinder, the mixture having been previously 95 compressed by the lower face of the lower annular piston. A channel or channels is or are provided to convey the mixture from the lower end of the cylinder to the upper end for delivery. The said channels 100 may be formed integrally with the cylinder wall.

Alternatively the upper piston may draw in mixture and the lower piston may draw in scavenging air.

Combustion therefore takes place between

the two annular pistons, (the one connected to the two outside cranks, and the other to the central crank.)

An ignition plug is fitted approximately 5 midway in the cylinder.

The sleeve connected to or formed integrally with the lower piston sliding upon the cylinder wall, serves not only to close the exhaust ports when the ports leading to the 10 carburetor or the like, are open for the induction of mixture to the lower pump, but it also serves to close the mixture inlet ports when compression of the mixture occurs for delivery to the working cylinder.

15 When the described construction is employed with a Diesel or semi-Diesel cycle both annular pumps may be employed for the delivery of air to the working cylinder.

20 And in order that my invention may be completely understood reference should be made to the accompanying sheets of drawings which illustrate one example of my invention diagrammatically.

25 Figure 1 is a vertical sectional elevation of a twin cylinder engine in the plane of the crank shaft, the right hand piston being shown in part section and in the position of maximum compression.

30 Fig. 2 is a section of the left hand cylinder shown in Fig. 1, but at a right angle therewith.

Fig. 3 is a plan section of the left hand cylinder of Fig. 1 on the line Y Y.

35 Fig. 4 is a plan section of Fig. 2, on the line X X.

Fig. 5 is a plan of the upper annular piston.

Like reference letters refer to like parts in each of the figures and the two cylinders shown in Fig. 1 having similar working parts in each cylinder have like reference letters.

40 A is the cylinder within which the two opposed pistons B and C reciprocate. The upper piston B of annular form is either rigidly secured to the tubular trunk B¹ or is integrally formed with it. The lower end of the trunk B¹ is formed with a bridge piece B⁵ secured to which, by the nuts 45 shown, is the detachable cross-head B², which crosshead carries the gudgeon pin B³ by which the connecting rod B⁴ is connected to the crank pin D¹ of the crank shaft D. The channels R and R¹ on each side of the 50 bridge piece B⁵ allow free passage of air to the crank chamber.

55 The cylinder cover A¹ has formed integrally with it, the tubular extension or sleeve A² which fits telescopically within the piston B and its trunk B¹. The cylinder A has formed on its inner surface the longitudinal passages E, which passages effect the transfer of the air, supplied as afterward described compressed or displaced by the 60 upper face of the annular piston B from the

annular space above the annular piston B to the lower side or working face of the said piston.

The lower or gudgeon pin end of the trunk B¹ fits telescopically and reciprocates 70 within the annular piston C. The piston C is similarly provided with the trunk or tubular extension C¹, which projects within the crank chamber F, and is provided at its lower end with the two lateral pins C² C³ 75 forming the gudgeon. Connected to the pins C² C³ are the connecting rods C⁴ C⁵ respectively. The big ends of these connecting rods fit the crank pins D² D³ of the crank shaft D.

80 The surface of the lower annular piston C reciprocates therefore upon the trunk B¹ of the upper annular piston as to its inner surface, but its outer surface slides upon the wall of the cylinder A, this outer surface 85 of the piston C is provided with a depending extension C⁶. The trunk C¹ also slides or reciprocates within the sleeve A³ formed integrally with the lower cylinder cover A⁴ which is secured to the crank chamber. As 90 shown the two cylinder covers A⁴ A⁴ closing the lower ends of the two working and pump cylinders A A, Fig. 1, are cast in one.

95 The two crank pins D² D³ move together having the same center line and the crank pin D being at 180 degrees to the other two, the two annular pistons B and C reciprocate toward and away from each other. In the left hand cylinder of the pair, Fig. 1, the pistons are shown at their dead points 100 at the maximum distance apart while in the right hand cylinder of Fig. 1, the two pistons are shown in the dead point position closest together. The space G in this cylinder between the two pistons therefore constitutes the combustion chamber of the engine.

105 The scavenging air enters the sleeve A² depending from the cover A¹ and passes through the ports H formed in the inner 110 wall of the annular piston B and then through the openings or ports in the upper wall of the piston, see Fig. 5. This entry of scavenging air takes place when the piston is at its lower dead point as shown in 115 the right hand cylinder, Fig. 1. When the piston reaches the upper dead point or somewhat before it, as shown in the left hand cylinder, the air is displaced through the longitudinal passage E to the working side 120 of the piston.

125 The mixture or new charge is drawn into the annular passage I, Figs. 1 and 3, and passes through the ports J when the lower piston C is in the position shown in the right hand cylinder into the annular pump chamber between the piston and the cover plate A⁴. The mixture is displaced by the return of the piston C to the position shown in the left hand cylinder, through 130

the port K into the duct or passage K¹, (Figs. 2, 3, and 4,) by which it is conveyed to the port K² and delivered to the working cylinder when the pistons are at their dead points as shown in Fig. 2. The compression takes place between the two annular pistons. At the maximum compression as shown in the right hand cylinder, Fig. 1, the charge is ignited and the explosion or combustion 10 takes place between the two pistons. At the end of the working stroke, the exhaust ports L are uncovered by the piston C, the exhaust gases pass by means of the annular passage L¹ to the exhaust outlet L², see Fig. 4. 15 Air is also drawn from the central tube through the ports H into the engine, and this in addition to the reciprocating movement of the lower piston into and out of the 20 crank chamber causes a draft of air to be continuously circulated through the central tubular channel.

It will be observed that the depending outer extension sleeve formed integrally with the lower annular piston serves as a closure 25 for the exhaust ports during the induction of the mixture to the lower annular pump.

What I do claim as my invention and desire to secure by Letters Patent is:—

1. In an internal combustion engine, the 30 combination of a cylinder, opposed annular pistons working in the cylinder, each of the pistons being provided with an opening extending centrally and longitudinally through the same, and one of the pistons 35 having a trunk extension extending from its central opening and slidably fitting within the opening of the other piston, a stationary sleeve at one end of the cylinder slidably engaging the said trunk extension, 40 said sleeve opening to the atmosphere at one end and communicating at its other end with the trunk extension, means for introducing an explosive charge into the cylinder between the pistons, and means for 45 igniting the charge.

2. In an internal combustion engine, the combination of a cylinder, opposed annular pistons working in the cylinder, said pistons being provided with concentric channels 50 extending centrally therethrough and with trunk extensions slidably engaging each other, a crank case at one end of the cylinder in communication with the trunk extensions of both of the said pistons, a stationary sleeve at each end of the cylinder fitting within and slidably engaging the trunk extension of one of the pistons, one of 55 said sleeves being open to the atmosphere at one end, means for introducing an explosive charge into the cylinder between the pistons, and means for igniting the charge.

3. In an internal combustion engine, the combination of a cylinder, opposed annular pistons working in the cylinder, each of the 60 pistons being provided with an opening ex-

tending longitudinally through the same, and with a trunk extension slidably fitting within the trunk extension of the other piston, fixed sleeves at opposite ends of the cylinder slidably fitting the respective trunk extensions, the respective sleeves and trunk extensions forming with the cylinder pump chambers at one side of the pistons, air inlet ports affording communication with one of said pump chambers and to the working space between the pistons, and mixture inlet ports affording communication with the other of said pump chambers and the working space between the pistons, the air inlet and mixture inlet ports being controlled by 75 the pistons, and means for igniting the charge in the working space between the pistons.

4. In an internal combustion engine, the combination of a cylinder, opposed annular 80 pistons working in the cylinder, each of the pistons being provided with an opening extending centrally and longitudinally through the same, and with trunk extensions extending from the said openings and slidably fitting one within the other, fixed sleeves at the opposite ends of the cylinder slidably fitting the respective trunk extensions, the sleeves and trunk extensions forming with the cylinder pump chambers 85 at one side of the pistons, air inlet ports affording communication with one of said pump chambers and the working space between the pistons, and mixture inlet ports affording communication with the other of 90 said pump chambers and the working space between the pistons, and means for igniting a charge in the working space between the pistons.

5. In an internal combustion engine, the 95 combination with a cylinder, opposed annular pistons in the cylinder, one of the pistons being provided with an opening extending centrally and longitudinally through the same, and with a trunk extension, a fixed 100 sleeve at one end of the cylinder, said sleeve opening at one end to the atmosphere and slidably fitting and communicating with the trunk extension, ports in the said piston adapted to be brought into communication 105 with the interior of the fixed sleeve when the piston is in its innermost position, said cylinder having passages adapted to form a communication between the space at one side of said piston and the working space 110 between the pistons during the return stroke of the piston, means for exhausting gas from the combustion space between the pistons, means for introducing an explosive charge into the working space between the 115 pistons, and means for igniting the charge.

6. In an internal combustion engine, the combination of a cylinder, opposed annular pistons working in the cylinder, both of the pistons being provided with open- 120

ings extending centrally and longitudinally through the same and one of the pistons having a trunk extension engaging the opening of the other piston, a fixed sleeve at one end 5 of the cylinder slidably engaging the trunk extension of one of the pistons, said sleeve being open to the atmosphere at one end and communicating with the said trunk extension, ports in one of the pistons adapted to 10 be brought into communication with the interior of the fixed sleeve when the said piston is in its innermost position, the cylinder having passages adapted to form a communication between the space at one 15 side of the said piston and the space between the pistons during the return stroke of the piston, means for exhausting gas from the space between the pistons, means for introducing an explosive charge between the 20 pistons, and means for igniting a charge between the pistons.

7. In an internal combustion engine, the combination of a cylinder, opposed annular pistons working in the cylinder, and connected respectively to the pistons, both pistons being provided with openings extending centrally and longitudinally through the same and with trunk extensions slidably fitting one within the other, a crank case at 25 one end of the cylinder in communication with the trunk extension of one of the pistons, a stationary sleeve at the other end of the cylinder fitting within and slidably engaging the trunk extension of one of the 30 pistons, said sleeve being open to the atmosphere at one end and in communication with the interior of the said trunk extension,

means for introducing an explosive charge into the cylinder between the pistons, and means for igniting a charge between the 40 pistons.

8. In an internal combustion engine, the combination of a cylinder, opposing pistons working in the cylinder, compression and combustion taking place between the pistons, 45 means at one end of the cylinder for delivering mixture between the pistons, said means including the outer face of one piston and a stationary sleeve extending within the cylinder from the head at one end thereof, and means for delivering compressed air between the pistons, said last mentioned means including the outer face of the other piston, and a stationary sleeve extending into the cylinder from the head at the other end of 50 the cylinder, substantially as described.

9. In an internal combustion engine, the combination of a cylinder, two opposing pistons working in the cylinder, compression and combustion taking place between 60 the pistons, said pistons having trunk extensions sliding one within the other, sleeves extending into the cylinder from the heads at opposite ends thereof slidably engaged by the trunk extensions, said sleeves forming an annular chamber at each end of the cylinder and constituting with the trunk extensions of the pistons a passage extending longitudinally and concentrically through the 65 engine and open to the atmosphere.

JAMES REGINALD KEMP.
